UNITED STATES PATENT OFFICE

2,561,086

STORM WINDOW SASH ADJUSTER

Paul L. Adams, Wayne A. Norman, and Charles K. Sitterly, Dubuque, Iowa, assignors to Carr, Adams & Collier Company, Dubuque, Iowa, a corporation of Iowa

Application July 21, 1949, Serial No. 105,948

2 Claims. (Cl. 292—263)

1

This invention relates to a storm window sash adjuster which contains many new features of design, and consequently offers advantages and improvements not heretofore found in such devices. This invention has for one of its principal objects to provide an adjuster which may easily, quickly, and without the aid of any tools be connected or disconnected from the storm sash. This we have accomplished in a new and unusual manner.

Other objects are to provide an adjuster which will also serve to lock the storm sash securely in a closed position, and to provide means whereby the adjuster will remain in any desired position.

Further objects such as simplicity, strength, durability, low cost, etc., will appear from the following description and drawings wherein.

Figure 1 is a perspective view of our sash adjuster in a partially opened position, shown attached to a window frame and storm sash;

Fig. 2 is a side elevation of the adjuster in the position which is reached just prior to its disconnection from the sash;

Fig. 3 is a side elevation of the adjuster in its openmost straight-out position;

Fig. 4 is a top plan view of the adjuster in its openmost position;

Fig. 5 is a side elevation of the adjuster in a partially closed position which it reaches just prior to being fully closed;

Fig. 6 is a side elevation of the adjuster in its fully closed position;

Fig. 7 is a side elevation of the adjuster in the position where it is fully closed and also swung upwardly through 180° to lock itself against opening;

Fig. 8 is a side elevation of the sash adjuster in a modified form wherein the link arm connected to the sash is formed of round stock such as heavy wire; and

Fig. 9 is a top plan view of the adjuster shown in Fig. 8.

Our new and improved window sash adjuster is in the form of a link comprising arms A and B made of metal or other suitable material. Arm A is formed with a long side wall 15, a short side wall 16 parallel with and opposed to the wall 15 and a connecting bottom 17 which terminates short of the ends of the wall 16. A channel that normally faces upwardly is thereby provided. The long side wall 15 is offset at 18 as shown in Fig. 4. Arm B may be made of flat stock as shown in Fig. 4, or of round heavy wire stock as shown in Figs. 8 and 9. This arm is formed with an elongated hook 19 at its outer end and a stake

2

20 outstanding from the arm about opposite the hook and forming a shoulder.

Arms A and B are pivotally joined as by means of a nut and bolt 21. In this assembly the arm B is sandwiched in between the walls 15 and 16 of the arm A and is separated therefrom by friction washers 22 (see Fig. 2) which are positioned wholly to the inside of the walls 15 and 16.

When in use the inner offset end of arm A 10 is pivotally secured to the frame 23 of a window as by means of a screw or bolt 24, and the outer end of arm B is secured to the sash 25 of the storm window by inserting the hook 19 into an eye fitting 26 of the ordinary common type which

15 may be attached in the usual manner to the storm sash. This is done by merely swinging the pivotally joined ends of the two arms A and B upwardly to a near top position, as shown in Fig. 2, and then feeding the hook into the eye.

20 This is possible due to the absence of any bottom or stop on arm A in the region of the pivot bolt 21 which allows the arm B to be swung through more than 270° until it fetches up against up against the bottom 17. By reversely swinging the

25 arms to the straight-line position (see Fig. 3) or further, the hook 19 is secured in the eye 26 and cannot be removed. To disconnect the hook 19 from the eye 26 it is merely necessary to swing the arms upwardly to a point well above the straight-line position (see Fig. 2) whereupon the link may be manipulated to effect the desired release.

To adjust the storm sash inwardly the arms are swung downwardly as shown in Fig. 5, and 35 when fully closed the arms will be in the position shown in Fig. 6. The stake 20 prevents the hook 19 from riding up into the eye 26 when the links A and B are in a swung-down position (see Figs. 5 and 6).

40 When the storm sash is fully closed, as in Fig. 6, it may be positively locked in such position by rotating the closed arms A and B upwardly 180° (see Fig. 7) from the normal closed position of the link shown in Fig. 6. The arm B is then prevented from opening outwardly by the bottom

45 17 of the arm A against which it rests. To release the arms from this locked position it is necessary merely to rotate the arms downwardly away from the storm sash to the position shown 50 in Fig. 6.

The friction washers 22 when compressed by properly adjusting the bolt 21 serve to adequately hold the link in any desired position, thus providing the widest possible range of adjustment 55 of the storm sash inwardly and outwardly.

We claim:

1. For use with a window frame wherein is a storm sash mounted to swing out at the bottom, an adjustment link for connection between the frame and sash near the bottom of each, comprising a flat frame arm having at one end means for pivotal connection with the frame, said frame arm being provided with a wall in spaced parallel and opposed relation to said frame arm and defining therewith a lengthwise channel open upon a long side and both ends, a sash arm provided with means for pivotal connection at one end with the sash and disposed within the channel of the frame arm, means providing a pivotal connection between the two arms and arranged to permit the sash arm to swing from a position within the channel of the frame arm outwardly thereof generating an angle between the two arms of more than 270°, the sash arm at its end remote from the frame arm being formed with a lengthwise slot opening laterally upon one edge of the arm and defining therewith an elongated hook for releasable engagement with an eye fitting upon the sash to provide therewith the pivotal connection aforesaid, said frame and sash links being swingable upwardly from a horizontal position to permit the hook to be fed into the eye fitting and downwardly from a horizontal position to adjust the sash, and carried by the closing movement of the sash into a downwardly extending folded position, and swingable upwardly from such position through an arc of 180° for locking the sash against opening movement, and a shoulder on the sash arm in the region of the hook proximate to the eye fitting and arranged to engage therewith for preventing releasing movement of the hook relative to the eye fitting when the frame and sash arms are in their downwardly extending folded position.

2. For use with a window frame wherein is a storm sash mounted to swing out at the bottom, an adjustment link for connection between the frame and sash near the bottom of each, comprising a flat frame arm having at one end means for pivotal connection with the frame, said frame arm being provided with a wall in spaced parallel and opposed relation to said frame arm and defining therewith a lengthwise channel open upon a long side and both ends, a sash

arm provided with means for pivotal connection at one end with the sash and disposed within the channel of the frame arm, means providing a pivotal connection between the two arms and arranged to permit the sash arm to swing from a position within the channel of the frame arm outwardly thereof generating an angle between the two arms of more than 270°, the sash arm at its end remote from the frame arm being formed with a lengthwise slot opening laterally upon one edge of the arm and defining therewith an elongated hook for releasable engagement with an eye fitting upon the sash to provide therewith the pivotal connection aforesaid, said frame and sash links being swingable upwardly from a horizontal position to permit the hook to be fed into the eye fitting and downwardly from a horizontal position to adjust the sash, and carried by the closing movement of the sash into a downwardly extending folded position, and swingable upwardly from such position through an arc of 180° for locking the sash against opening movement, a shoulder on the sash arm in the region of the hook proximate to the eye fitting and arranged to engage therewith for preventing releasing movement of the hook relative to the eye fitting when the frame and sash arms are in their downwardly extending folded position, and friction means associated with the pivotal connection between the two arms to impose resistance to swinging movement therebetween, whereby the two arms of the adjustment link are normally held against pivotal movement with respect to each other.

PAUL L. ADAMS.
